(57) **CLAIM**

The ornamental design for a quick release snowmobile seat, as shown and described.

DESCRIPTION

FIG. 1 is a perspective illustration, from the front and right side, of the quick release snowmobile seat of our design; FIG. 2 is a left side view thereof, the right side being a mirror image;

FIG. 3 is a front view thereof;

FIG. 4 is a rear view thereof; and,

FIG. 5 is a top view thereof;

The broken line showing of the interior of the seat is for illustrative purposes only and forms no part of the claimed design.
